US00D882407S

(12) United States Design Patent (10) Patent No.: US D882,407 S
(45) Date of Patent: * Apr. 28, 2020

(54) PACKING BOX

(71) Applicant: HISAMITSU PHARMACEUTICAL CO., INC., Tosa-shi, Saga (JP)

(72) Inventors: Sayaka Mochizuki, Tokyo (JP); Shigeo Kusumi, Tokyo (JP)

(73) Assignee: HISAMITSU PHARMACEUTICAL CO., INC., Tosa-Shi, Saga (JP)

() Term: 15 Years

(21) Appl. No.: 29/677,093

(22) Filed: Jan. 17, 2019

(30) Foreign Application Priority Data

Dec. 20, 2018 (JP) 2018-027867

(51) LOC (12) Cl. 09-01

(52) U.S. Cl. ..... USPC D9/614; D9/432

(58) Field of Classification Search

USPC D9/414-423, 424-429, 430-433, 434, D9/456, 457, 711, 713, 721-722, 737, D9/756, 758, 759, 760, 600, 614, 621, D9/623, 624; D3/272-274, 290, 304, D3/305, 315; D20/10, 22, 27, 40, 42

CPC ... B65D 5/00; B65D 5/02; B65D 5/18; B65D 5/20

See application file for complete search history.

(57) CLAIM

The ornamental design for a packing box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a packing box of the present invention;

FIG. 2 is a front view thereof;

FIG. 3 is a rear view thereof;

FIG. 4 is a top plan view thereof;

FIG. 5 is a bottom view thereof;

FIG. 6 is a right side view thereof; and,

FIG. 7 is a left side view thereof.

The features shown in broken lines depict environmental subject matter only and form no part of the claimed design.

1 Claim, 7 Drawing Sheets
(2 of 7 Drawing Sheet(s) Filed in Color)
